UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

RIBBON MECHANISM FOR TYPEWRITERS.

Application filed June 8, 1922. Serial No. 566,759.

To all whom it may concern:

Be it known that I, OTTO A. HOKANSON, a citizen of the United States, residing at Woodstock, in the county of McHenry and State of Illinois, have invented certain new and useful Improvements in Ribbon Mechanism for Typewriters, of which the following is a specification.

This invention relates to ribbon spools and positioning devices therefor together with the combination of said spools and devices with mechanism for controlling the feeding of the ribbon and especially the reversal of the ribbon when it has been unwound from a ribbon spool. It has for its object the provision of mechanism of the class named which shall be of improved construction, convenient and efficient in operation, and economical to manufacture.

The invention is exemplified in the combination and arrangement of parts shown in the accompanying drawing and described in the following specification, and it is more particularly pointed out in the appended claims.

In the drawing—

Fig. 1 is a vertical section of a ribbon spool mounting having one embodiment of the present invention applied thereto;

Fig. 2 is a top plan view of the ribbon spool spindle with the spool removed; and

Fig. 3 is a transverse section of a ribbon spool comprising a part of the present invention.

In my prior Patent No. 1,385,548, issued July 26, 1921, I have shown an automatic ribbon reversing mechanism controlled by the ribbon as it is unwound from one or the other of the spools. The present invention is in the nature of an improvement upon the controlling mechanism for the automatic ribbon reverse shown in that patent.

In the drawing, the numeral 10 designates a portion of the top plate of a typewriter having a ribbon spool casing 11 mounted thereon. A spindle 12 is journaled in a bushing 13 supported on the frame plate 10. A ratchet wheel 14 is secured to the spindle 12 below the plate 10 and is operated by pawls 15 in the manner described in my prior patent. The spindle 12 receives a ribbon spool 17 on its upper end upon which the ribbon is wound and un-

wound alternately during typewriting operations.

The spool 17 is built up of sheet metal and comprises a pair of duplicate heads 18 connected by a central drum 19. The drum 19 consists of a single sheet of metal bent, as shown in Fig. 3, to provide a core member upon which the ribbon is wound and a central socket 20 for receiving the upper end 21 of the spindle 12. The edges of the core member 19 are received in grooves 22 struck outwardly on the spool heads 18 and the heads are secured to the core by tongues 23 formed on the socket 20 and bent over on the outside of the heads 18. The socket portion 20 is connected with the outer portion of the spool 19 by flat parallel parts 24 and suitable barbs 25 are struck out from the core to engage the end of the ribbon wound upon the spool.

The spool heads 18 are each provided with openings 26 for receiving a trip finger 27 by which the reversing mechanism is operated. Each head is also provided with a notch 28 disposed opposite the opening 26 for receiving a spring 29 which controls the trip finger 27. The heads 18 are duplicates of one another so that the spool may be placed upon the spindle either side up.

The spindle 12 is provided with an enlargement 30 which forms a shoulder upon which the spool 17 rests. The trip finger 27 is supported upon a yoke 31 which is arranged astride the enlargement 30 and pivoted thereto by screws 32. A finger 33 on the yoke 31 engages the spring 29 at a point above the pivotal center of the yoke, as shown in Fig. 1, so that the spring normally tends to rotate the yoke in a clockwise direction, as viewed in that figure, urging the trip finger 27 toward the spindle 12.

The spring 29 is secured to the upper end of the spindle 12 by a screw 34 which passes through an opening in the upper end of the spring 29 and is threaded into an opening 35 in the upper end of the spindle. The spring 29 may be provided with a downwardly bent portion for engaging a depression in the upper end of the spindle 12 to properly locate the spring relative to the spindle. The lower end of the spring is located in a notch or recess 36 formed in the enlargement 30 into which recess the finger 33 of the yoke 31 projects. The spring 29 is

received in the recesses 28 so that the ribbon spool is located upon the spindle by the engagement of the spring with these recesses. This serves as a driving connection between the spool and spindle and also properly locates the opening 26 to receive the trip finger 27 when the spool is placed upon the spindle.

The spring 29 is offset at 37 to form a yielding stop to retain the spool upon the spindle. A vertically sliding rod 38 is provided with a contact member 39 for operating the ribbon reversing mechanism in the manner explained in my patent mentioned above. When the spool is removed from the spindle 12 the spring 29 shifts the control finger 27 into position adjacent the spindle so that when the spool is replaced the finger will enter the space within the core 19 and within the ribbon wound upon the core through the opening 26 in the lower spool head 18. In replacing the spool the rounded head of the screw 34 serves as a guide to direct the spindle 12 into the socket 20 and since the upper end of the spindle projects above the upper end of the finger 27 the spool will be properly located to receive the finger before it is moved downwardly to a level with the upper end of the finger. This will avoid any danger of inserting the trip finger between the folds of the ribbon. As soon as the finger is properly located within the space at the interior of the ribbon the spring 29 will be depressed leaving the trip finger and its yoke 31 free to move upon the pivot screws 32. The finger will rest against the inner turn of the ribbon until the ribbon has been unwound from the spool at which time the finger will fall into the position shown in Fig. 1 and effect a reversal of the ribbon feeding mechanism.

It will be seen that a simple and efficient construction is provided and one which will operate to insure proper relation of the parts when a spool is placed upon the spindle irrespective of any especial attention on the part of the operator.

I claim:

1. Ribbon mechanism for typewriters comprising a spool, a spindle for said spool, a control member, and a spring for positioning said control member, said spring being connected with said spindle in position to enter within said spool when said spool is placed upon said spindle.

2. Ribbon mechanism for typewriters comprising a spool, a spindle for receiving said spool, a ribbon controlled device arranged to enter said spool when said spool is placed upon said spindle, a spring for positioning said device, and means on said spool for engaging said spring to position said spool on said spindle.

3. Ribbon mechanism for typewriters

comprising a spool, a spindle for receiving said spool, a control device connected with said spindle in position to enter said spool, and a single means for positioning said control device in proper relation to said spindle to enter said spool as said spool is moved onto said spindle, said means having a portion thereof adjacent the end of said spindle in position to prevent movement of said spool onto said spindle except when said spool is properly located relative to said spindle so that said control device will properly enter said spool when said spool is placed upon said spindle.

4. Ribbon mechanism comprising a spindle, a spool movable into and out of position thereon, and a spring attached to said spindle and projecting laterally therefrom at the end thereof and arranged to enter said spool to position said spool on said spindle.

5. Ribbon mechanism comprising a spindle, a spool movable into and out of position thereon, and a spring connected with the outer end of said spindle and projecting laterally therefrom adjacent said end and extending in the direction of the length thereof, said spool having a recess therein arranged to register with said spring when said spool is placed on said spindle.

6. Ribbon mechanism for typewriters comprising a spool, a spindle for supporting said spool, a control member mounted on said spindle, and a spring carried by said spindle for positioning said control member to enter said spool, said spool having a recess therein to receive said spring and hold said spool and spindle against relative rotation.

7. Ribbon mechanism for typewriters comprising a spool, a spindle for supporting said spool, a trip finger connected with said spindle, and a spring mounted on said spindle for moving said trip finger toward said spindle, said spring engaging said spool to hold said spool on said spindle and prevent relative rotation thereon.

8. Ribbon mechanism comprising a spool, a support therefor, a control device associated with said spool when in position on said support, and a single spring for positioning said control device relative to said spool and for retaining said spool on said support and for preventing rotation of said spool relative to said support.

9. Ribbon mechanism for typewriters comprising a spool, a spindle for receiving said spool having an enlarged portion thereon, a yoke pivoted on said enlarged portion, a finger carried by said yoke for engaging the ribbon on said spool, a spring acting radially relative to said spool for moving said yoke upon its pivot, and a contact device integral with said yoke for engaging said spring.

10. Ribbon mechanism comprising a spool, a support for said spool, a control device arranged to cooperate with the ribbon on said

- spool, a yoke for said control device pivoted on said support, a spring acting radially relative to said spool for positioning said control device, and means integral 45 with said yoke for engaging said spring, said spring being directly engaged by said spool when said spool is in position on said support to hold said spring in an inactive position relative to said yoke.
- 5 10. Ribbon mechanism comprising a spool, a spindle for supporting said spool, a control device pivoted on said spindle for engaging the ribbon on said spool, a spring carried by said spindle and extending in the direction of the length thereof, and means connected with said control device for engaging said spring to normally move said control device into close relation with said spindle, said spool engaging said spring to compress the same and free said control device 50 therefrom when said spool is in position on said spindle.
- 15 11. Ribbon mechanism comprising a spindle, a ribbon spool, a control device for engaging the ribbon on said spool when said spool is on said spindle, means for directing said spool onto said spindle and acting radially relative thereto, a spring connected with said spindle for positioning said control device, means on said spool for engaging said spindle to compress said spring and free said control device therefrom as said spool is moved onto said spindle, the compression of said spring taking place subsequent to the 55 movement of said spool into registration with said control device.
- 20 12. Ribbon mechanism comprising a spindle, a spool having a socket for receiving said spindle, a trip finger pivoted on said spindle to enter said spool and engage the ribbon thereon, a spring extending longitudinally on said spindle, means connecting said spring with said trip finger to hold said 60 trip finger in close relation with said spindle when said spring is unrestrained, and means on said spool for engaging said spring to compress said spring during the movement of said spool onto said spindle, said spool being positioned by said spindle to receive said trip finger prior to registration between said spool and said trip finger and the compression of said spring taking place subsequent to the registration between said spool and trip finger.
- 25 13. Ribbon mechanism comprising a spool, a spindle for receiving said spool, a control device for entering said spool when said spool is placed upon said spindle, and means for locating said spool on said spindle in position to receive said control device, said locating means comprising a spring for engaging said spool and attached to said spindle adjacent the engaging portion thereof said portion being positioned to act prior to the registration of said control device and spool 65 during the movement of the spool onto said spindle.
- 30 14. Ribbon mechanism comprising a spool, a spindle for receiving said spool, a control device for entering said spool when said spool is placed upon said spindle, and means for locating said spool on said spindle in position to receive said control device, said locating means comprising a spring for engaging said spool and attached to said spindle adjacent the engaging portion thereof said portion being positioned to act prior to the registration of said control device and spool 70 during the movement of the spool onto said spindle.
- 35 15. In combination, a ribbon spool, a spindle for supporting said spool, a control device mounted on said spindle and arranged to enter an opening in said spool when said spool is moved onto said spindle, and means on said spindle for angularly positioning said spool to cause the opening therein to register with said control device, said locating means being positioned on said spindle at the outer end thereof to be brought into cooperation with said spool prior to the registration of said control device with said opening when the spool is moved onto said 75 spindle.
- 40 16. In testimony whereof I have signed my name to this specification on this 2nd day of June, A. D. 1922.
- 45 OTTO A. HOKANSON.
